SPECTACLE FRONT

Raymond F. E. Stegeman, Greece, N. Y., assignor
to Bausch & Lomb Optical Company, Roch-
ester, N. Y., a corporation of New York

Application February 17, 1950, Serial No. 7,988

Term of patent 14 years

(Cl. D57—1)

To all whom it may concern:

Be it known that I, Raymond F. E. Stegeman, a citizen of the United States and a resident of the town of Greece, county of Monroe, and State of New York, have invented a new, original, and ornamental Design for a Spectacle Front, of which the following is a specification, reference being had to the accompanying drawing, forming a part hereof.

Fig. 1 is a front elevational view of a spectacle front, showing my new design.

Fig. 2 is a top plan view thereof.

My design for a spectacle front is characterized by a difference in the appearance of the materials used in the bridge and the upper rim portions, all as illustrated.

I claim:

The ornamental design for a spectacle front, substantially as shown and described.

RAYMOND F. E. STEGEMAN.
